UNCURLER GUIDE FOR CUP FEED SEWING MACHINES

Frank A. Kucera, Chicago, Ill., and Robert Brock, Brooklyn, N. Y., assignors to Union Special Machine Company, Chicago, Ill., a corporation of Illinois

Application June 5, 1940, Serial No. 338,918

14 Claims. (Cl. 112—20)

The invention relates to uncurler guides for "cup feed" sewing machines such as are commonly used to seam full fashioned stockings and the like.

In the usual types of uncurler guides, the clamp members between which and a central tongue, the edges of the fabric are passed for removal of the natural edge curl before entering between the feed cups or wheels by which said edges are intermittently advanced and presented to the stitch forming instrumentalities of the machine, are suspended from horizontal hinge pivots and thus are capable only of parallel movement relative to the tongue. Accordingly the clamp members cannot adapt themselves positionally to variations in the thickness of the material being seamed, and therefore fail at times to guide the material with accuracy and positiveness, particularly when the fabric is formed from hard and slippery yarn.

Our invention has for its chief aim to overcome the above drawback, which objective we attain as hereinafter more fully disclosed, by mounting the clamp members in such a way that they are free to move not only in parallel relation to the central tongue of the uncurler guide, but about horizontal and vertical axes as well as thickness irregularities pass between them and the tongue, to the end that the material is kept under definite control and its edges are uniformly advanced in a straight line by the feed cups to the stitching instrumentalities of the sewing machine.

Other objects and attendant advantages will appear from the following detailed description of the attached drawings, wherein

Fig. 1 is a fragmentary view showing, in front elevation, a cup feed sewing machine conveniently embodying the uncurler guide of our invention.

Fig. 2 is a side elevation of the machine looking from the left of Fig. 1.

Figs. 3 and 4 are detail cross sectional views of the uncurler guide drawn to a larger scale and taken as indicated respectively by the angled arrows III—III and IV—IV in Fig. 2.

Fig. 5 is a perspective view of one of the clamp members of the guide.

Figs. 6 and 7 are views corresponding to Figs. 1 and 2 showing an alternative embodiment of our invention.

Fig. 8 is a detail view in section taken as indicated by the angled arrows VIII—VIII in Fig. 6; and

Fig. 9 is a perspective view of the central or tongue member of the guide shown in Figs. 6 and 7.

The sewing machine partly illustrated in Figs. 1 and 2 is generally of the construction set forth in U. S. Patent No. 2,292,762, granted to Frank A.

Kucera on August 11, 1942, its overhanging frame arm being shown at 10 and its peripherally-corrugated tangentially-opposed horizontally-arranged feed cups or wheels at 11 and 12. It is to be understood that the shafts 13 and 14 for the feed cups 11 and 12 pass up into the frame portion 10, and that they are intermittently rotated by suitable mechanism within the machine housing in timed relation with the endwise reciprocations of the horizontal needle indicated at 15. It is to be further understood that suitable instrumentalities including an over-edge looper cooperate with the needle 15 as in the patent supra, in forming an over-edge seam. Supported by the overhanging frame arm 10 at the front of the machine with capacity for vertical adjustment by a regulating means 16, is a block 17 which carries a bearing 18 for a short transverse shaft 19. Affixed to one end of the shaft 19 is a collar 20 whereto our improved uncurler guide, comprehensively designated by the numeral 21, is secured. On the opposite end of the shaft 19 are mounted notched cam disks 22 and 23, which, by cooperation with a spring pressed dog or detent 24, serve to hold the uncurler guide in the normal position in which it is shown in Figs. 1 and 2, or in various retracted angular positions in the manner shown and explained in the hereinbefore referred to patent.

In the form illustrated in Figs. 1 and 2, our improved uncurler guide 21 includes a central tongue member 25 of relatively thin but stiff sheet metal. As shown, the tongue 25 is secured at its upper end by a plurality of rivets 48, to an attaching plate 27, which, at the back, has a transverse ridge 28 fitting into a transverse recess 29 in a pendant arm projection 30 on the collar 20 and which is removably secured to said projection by cap screws 31. The lower end of the tongue 25 has the form of a boot, with its toe 26 extending rearwardly of the direction of feeding indicated by the arrow in Fig. 2. Arranged at opposite sides of the tongue 25 are clamp members 32 and 33 which have configuration similar to that of the tongue but which are of smaller dimensions. The toe ends 34 of the clamp members 32 and 33 curve outwardly as at 35, to facilitate entry between them and the contiguous side faces of the tongue 25, of the selvage edges E (Figs. 3 and 4) of the stocking fabric S which are to be united. The upper edges of the toe ends 34 of the clamp members 32 and 33 are upwardly rounded as at 36 so as to engage within the curls C of the fabric edges E and to gradually flatten them out before they are presented to the stitching needle 15 under the progressing action of the feed cups 11 and 12. Each clamp member 32 and 33 has apertures 37 and 38, one in its upper or shank portion, and the other in its heel portion, which respectively engage over round-ended stud

projections 39 and 40 at opposite sides of the central tongue 25, the last mentioned stud projections constituting a top guide for the fabric edges as clearly shown in Fig. 2. It is to be particularly noted from Figs. 3 and 4 that the apertures 37 and 38 are considerably larger than the studs 39 and 40. Each clamp member 32, 33 is moreover formed in its top edge with a notch 41 for loose vertical sliding guidance by additional stud projections 42 at opposite sides of the central tongue 25. Secured at its lower end to the outer side of each clamp member 32, 33 approximately at the center by a screw 43, is an outwardly bowed leaf spring 45, which, adjacent its free upper end, has a vertical slot 46 for capacity to engage over the corresponding stud projection 39 on the tongue 25, said slot being considerably wider than said projection as will be readily seen from Figs. 2, 3 and 4. Also from Figs. 2 and 5, it is important to note that the bow springs 45 taper downwardly toward their lower ends so as to have minimum contact area with the clamp members 32, 33 at the region of their anchorage by the screws 43. As shown in Fig. 1, the studs 39 are threaded for thumb nuts 47 whereby the pressing action of the springs 45 upon the clamp members 32 and 33 may be accurately regulated. For convenience and ease of construction, the studs 39, 39, 40, 40 and 42, 42 are formed respectively from single pins which are passed through the tongue 25 and suitably anchored in the latter at their centers.

Due to loose fit between the apertures 37, 38 and the notches 41 in the clamp members 32, 33 and the studs 39, 40 and projections 42, and by reason of the connection of the spring 45 to the clamp members approximately at the centers of the latter, said members are accorded capacity for limited independent universal movement relative to the center tongue 25.

As a consequence, the clamp members are able to adapt themselves positionally to variations in the thickness of the passing fabric edges as instanced in Fig. 4, where the toes of said members are riding the thickened reinforced heel portions H of the stocking, while their heels are riding the thinner portions F of the stocking sole. Side-wise rocking of the clamp members 32 and 33, will be yieldingly resisted by torsional action of the springs 45, since no relative motion between the lower end of the spring and its clamp member is possible.

In the alternative embodiment of our invention, shown in Figs. 6-9, the center tongue of the uncurler and its attaching plate 27a are integrally formed, and the clamp members 32a, 33a held to central position in respect to the studs 39a by guide pins 50 and 51 which are so spaced as to allow the requisite freedom of movement of said members for their positional adaptation to fabric thickness variations. Another departure from the first described embodiment will be observed in that the bow springs 45a are pierced adjacent their upper ends to loosely engage stud projections 52 on the attaching plate 27a of the central tongue, while their opposite ends bear against the outer sides of the clamp members 32a, 33a at regions somewhat above the level of the studs 40a. In all other respects the construction of the alternative embodiment of our invention is like the first described form. Therefore, in order to preclude duplicity in description corresponding parts are designated by the same reference characters previously employed, except for the addition in

each instance of the exponent a for convenience of ready distinction.

Having thus described our invention, we claim:

1. An uncurler guide for cup feed sewing machines comprising a flat central tongue; flat fabric clamping members respectively at opposite sides of the central tongue; means whereby the clamping members are supported with capacity for limited universal movement relative to the side faces of the tongue, so that they may adapt themselves positionally to variations in the fabric edges passed between them and the side faces of said tongue; a pair of bowed leaf springs each with one end bearing on the tongue and the other end bearing on the outside of one of the clamping members to urge the latter yieldingly toward the tongue; and abutments against which the springs bear intermediate their ends, said abutments being adjustably supported by said tongue so that the pressure of the springs may be varied.

2. An uncurler guide for cup feed sewing machines comprising a flat central tongue; lateral stud projections at opposite sides of the tongue; flat clamping members having apertures of a size to fit loosely over the stud projections so that said members may have the capacity for limited universal movement to adapt themselves positionally to thickness variations in the fabric edges passed between them and the tongue; and means for yieldingly urging the clamping members toward the tongue, including bowed leaf springs with openings in them to respectively clear the stud projections with looseness, said springs being secured at one end to the out-sides of the respective clamping members approximately at the centers of the latter, and abutments adjustable along the stud projections to regulate the pressure of the springs.

3. An uncurler guide for cup feed sewing machines comprising a flat central tongue; lateral stud projections at opposite sides of the tongue; flat clamping members having apertures of a size to fit loosely over the stud projections so that said members may have the capacity for limited universal movement to adapt themselves positionally to thickness variations in the fabric edges passed between them and the tongue; and means for yieldingly urging the clamping members toward the tongue including bowed leaf springs with medially located apertures to respectively clear the stud projections with looseness, said springs bearing at one end upon the out-sides of the tongue member and at the other end upon the out-sides of the respective clamping members, and abutments adjustable along the stud projections to regulate the pressure of the springs.

4. An uncurler guide for cup feed sewing machines comprising a central tongue, fabric clamping members respectively at opposite sides of the tongue; means whereby each clamping member is supported with capacity for accommodating itself to variations in the thickness of the fabric passing between it and the tongue while maintaining uniform pressure over the clamped area of the fabric; arcuate leaf springs individually secured at one end to the out-sides of the respective clamping members; and abutments carried by the tongue against which the leaf springs bear.

5. An uncurler guide according to claim 4, in which the abutments are individually adjustable to vary the pressure of the respective springs.

6. An uncurler guide for cup feed sewing machines comprising a central tongue; fabric clamping members respectively at opposite sides of

the tongue; means whereby each clamping member is supported with capacity for accommodating itself to variations in the thickness of the fabric passing between it and the tongue while maintaining uniform pressure over the clamped area of the fabric; a pair of bowed leaf springs each with one end bearing on the tongue and the other end bearing on the out-side of one of the clamping members to urge the latter yielding toward the tongue; and abutments against which the respective springs bear intermediate their ends, said abutments being adjustably supported by said tongue so that the pressure of the springs may be varied.

7. An uncurler guide for cup feed sewing machines comprising a central tongue; lateral stud projections at opposite sides of the tongue; clamping members at opposite sides of the tongue each having an aperture of a size to fit loosely over the stud projections so that it can accommodate itself to variations in the thickness of the fabric passing between it and the tongue while maintaining uniform pressure over the clamped area of the fabric; and means for yieldingly urging the clamping members toward the tongue including leaf springs with openings in them to respectively clear the stud projections with looseness, each such spring being secured at one end to the out-side of the corresponding clamping member, and abutments adjustable along the stud projections to regulate the pressure of the springs.

8. An uncurler guide for cup feed sewing machines comprising a central tongue; lateral stud projections at opposite sides of the tongue; clamping members at opposite sides of the tongue each having an aperture of a size to fit loosely over said stud projections so that it can accommodate itself to variations in the thickness of the fabric passing between it and the tongue while maintaining uniform pressure over the clamped area of the fabric; and means for yieldingly urging the clamping members toward the tongue including leaf springs with medially spaced apertures to respectively clear the stud projections with looseness, each such spring bearing at one end upon the out-side of the tongue member and at the other end upon the out-side of the corresponding clamping member, and abutments adjustable along the stud projections to regulate the pressure of the springs.

9. An uncurler guide for cup feed sewing machines comprising a flat central tongue; flat fabric clamping members respectively at opposite sides of the tongue; means for supporting the clamping members with capacity for limited universal movement relative to the side faces of the tongue so that they can adapt themselves positionally to variations in continuous fabric edges passing between them and said side faces; articulate leaf springs secured at one end to the out-sides of the respective clamping members approximately at the centers of the latter over relatively small restricted areas and abutments carried by the tongue against which the opposite ends of the leaf springs bear, said abutments being adjustable to vary the pressure of the springs.

10. An uncurler guide for cup feed sewing machines comprising a central tongue; fabric clamping members at opposite sides of the tongue

between which members and tongue separate continuous fabric edges are passed; means for supporting the clamping members from the tongue with capacity for individual angular movement relative to the respective contiguous sides of said tongue in the direction of fabric feeding, so that said clamping members can adapt themselves to thickness variations in the respective fabric edges while bearing fully on said edges; bow springs with corresponding ends thereof engaging the respective clamping members; and adjustable abutments engaged by the intermediate portions of said springs.

11. An uncurler guide for cup feed sewing machines comprising a central tongue; fabric clamping members at opposite sides of the tongue between which members and tongue separate continuous fabric edges are passed; means for supporting the clamping members loosely with capacity for individual angular movement relative to the contiguous sides of said tongue in the direction of fabric feeding, so that said members can adapt themselves to thickness variations in the respective fabric edges while bearing fully on said edges; bow springs with corresponding ends thereof engaging the respective clamping members; and adjustable abutments engaged by the intermediate portions of said springs.

12. An uncurler guide for cup feed sewing machines comprising a central tongue; studs extending laterally from opposite sides of the tongue; clamping members at opposite sides of the tongue between which members and tongue separate continuous fabric edges are passed, each such member having an aperture of a size to fit loosely over the corresponding stud; means for supporting the clamping members with capacity for individual angular movement relative to the contiguous sides of the tongue in the direction of fabric feeding, so that said members can adapt themselves to thickness variations in the respective fabric edges while bearing fully on said edges; bow springs with corresponding ends thereof engaging the respective clamping members; and adjustable abutments engaged by the intermediate portions of said springs.

13. An uncurler guide for cup feed sewing machines, comprising a central tongue; clamping members at opposite sides of the tongue; bowed springs with corresponding ends thereof engaging the respective clamping members; and adjustable abutments engaged by the intermediate portions of said springs.

14. An uncurler guide for cup feed sewing machines comprising a central tongue; fabric clamping members respectively at opposite sides of the tongue; means whereby each clamping member is supported with capacity for adapting itself to variations in the thickness of the fabric passing between it and the tongue while maintaining uniform pressure over the clamped area of the fabric; a pair of associated bowed leaf springs each with one end bearing on the tongue and the other end bearing on the out-side of one of the clamping members; and separate spring compressing devices supported by the tongue and engaging the intermediate portions of the springs for urging the clamping members into yielding engagement with said tongue.
